UNITED STATES PATENT OFFICE.

JOHN WILKINSON GREIG, OF IVANHOE, VICTORIA, AUSTRALIA.

VACUUM-PRODUCING APPARATUS.

Application filed June 18, 1923. Serial No. 646,255.

To all whom it may concern:

Be it known that I, JOHN WILKINSON GREIG, a subject of the King of Great Britain, residing at Waverley Avenue, Ivanhoe, in the State of Victoria, Commonwealth of Australia, have invented certain new and useful Improvements in Vacuum-Producing Apparatus; and I do declare the following to be a full, clear, and exact description of the invention, such as will enable others skilled in the art to which it appertains to make and use the same.

This invention relates to an improved vacuum producing apparatus and has been devised in order to provide simple and efficient means for accomplishing this result.

Many are the advantages which a vacuum possesses for use in various trades, processes and professions and it is with an object of definitely obtaining a vacuum in a simple and efficient manner that the present invention has been devised.

An essential feature embodied in this invention consists in forcing water, steam or other fluid through a tube of substantially small diameter, the exhaust end of which connects a delivery pipe enclosed within a water seal chamber having a concave bottom and an outlet pipe disposed substantially above the lower end of the delivery pipe, which is so disposed within the water seal chamber that as the water or steam is exhausted it strikes the concave surface at or about the commencement of its curve and so causes the fluid to swirl about the mouth of the delivery pipe and completely cover same to prevent any air return, the inlet pipe being provided with a by-pass leading to a pressure chamber having a pipe leading thereto with a valve control from the vessel from which the air or gas is to be exhausted.

A further essential feature consists in the leading of the delivery pipe into a water seal and close to the concave surface at the bottom of the water seal chamber so as to cause the water on contact with a conical projection on the concave surface to swirl above the delivery outlet to prevent any air return through the delivery pipe.

A further essential feature consists in terminating the inlet pipe in a jet in a pressure chamber having a pipe line with valve control leading to it from the vessel to be exhausted and mounting by a screw thread in the outer wall of the pressure chamber in

line with the jet a combining tube having outwardly flaring or enlarged tapering ends, the threading of the tube allowing of the widening or closing of the space between the tube and the jet as required and to allow of varying pressures to be obtained.

In order that the invention may be more readily understood it will now be described with reference to the accompanying drawings in which:—

Figure 1 is a view in vertical central section of one form of machine embodied in the invention.

Figure 2 is a view in vertical central section of an alternative construction of vacuum producing machine.

Figure 3 is a perspective view of an essential part.

Fig. 4 illustrates the structure Fig. 1 provided with the chamber 29 of Fig. 2.

According to this invention and as illustrated in Figure 1 a pipe lead 1 is taken from a suitable source, which may consist of steam, water or compressed air, the entry thereof into the pipe being preferably in a downward and vertical direction.

The bore 2 of the pipe line 1 referred to commences to decrease in internal diameter from the point where the fluid enters, the reduction continuing until the passage assumes the horizontal as at 5, and preferably the maximum reduction is disposed at a point 6 at right angles to the fluid inlet portion.

Cast integral with the pipe line 1 described is a flange 4 adapted to engage an inturned flange of a pressure chamber 3.

The pipe line extends into the chamber in the form of a jet member 8.

The chamber 3 is open at one end 10 and at the other end being formed with a tapped orifice 11 adapted to receive the correspondingly screwed flange of an adjustable combining tube 13 which is substantially longer than the jet member 8 previously described, the inner opening 14 in the combining tube 13 being in line with the smaller jet member 8 but a definite space is maintained between them to form a gap 15.

The object of screwing the combining tube 13 is for adjusting the gap 15 between it and the smaller jet 8 thus providing means for the definite regulation of the space between the combining tube and the jet and thus allowing of variable pressures being obtained.

The combining tube 13 is formed with outwardly flared or conical passages 16 and 17 at both ends and the outer or exhaust end 17 projects beyond the exterior wall 18 of the pressure chamber 3 so as to allow the fluid after passing through the passage 2 and jet 8 to exhaust therethrough and into any pipe line connected to the end 17 for the purpose of carrying the waste to any suitable source of outlet.

Disposed on a convenient part of the pressure chamber 3 and in communication therewith is a pipe line 19 leading to the vessel wherein it is desired to create a vacuum, the pipe line 19 having a valve 20 thereon to retain the vacuum in the vessel 3 when once created, and a gauge may be disposed upon the pipe line 19 between the valve 20 and the vessel so that the vacuum obtained may be readily ascertained.

The power fluid is preferably driven through or past a helix 21 disposed in an enlarged portion at the entrance of the pipe 1.

This helix 21 functions so that not only does it give the water a rotary motion but it divides the water in its flow through the passage 2 so forming air pockets allowing the air to be exhausted to be carried away through the combining tube 13, and the said helix is preferably shaped as illustrated in Figures 3, the top portion 21^a being set at right angles to the bottom portion 21^b.

In this construction the operation consists of feeding the fluid past the helix which gives it a rotary motion through the reducing passage 2 and also splits the same into air pockets which are delivered into the pressure chamber 3.

The combining tube 13 having been adjusted to suit the pressure required forms the exhaust for the fluid and the air which has filled the air pockets and which has been drawn from the vessel in which the vacuum is being created.

In the construction illustrated in Figure 2 a pipe lead 22 is taken from any suitable source of supply and this supply may consist of steam, water or compressed air, the entry thereof into the pipe being preferably in a downward and vertical direction.

The top 23 of the pipe lead 22 is fitted with the helix 21 functioning in the manner above described.

The pipe line referred to decreases in internal diameter as at 22^a in the form of a throat from the point where the fluid leaves the helix 21, the reduction continuing past the diagonal by-pass 24 leading to a pressure chamber 25, the by-pass 24 being of substantially smaller diameter than the minimum diameter in the reducing pipe 22.

Cast integral with the pipe line 22 described is a flange 26 adapted to be fitted to a corresponding flange 27 of a pressure chamber 25 which is mounted on a chamber

29 containing liquid and forming a liquid seal or containing the exhausted element only.

Depending from the top of the liquid chamber and centrally therein is an extension tube 30 the upper end of which receives the lower end of the pipe 22, the lower portion of said pipe 22 below the by-pass 24 flaring outwardly and downwardly as at 31 to provide an increased area for the passage of fluid, which passing down the tube 30 strikes the point of the projection 32 extending from the concave base of the liquid seal chamber 29 and is split to swirl about the end of the tube 30 to prevent the return of air and the fluid and air then passing through the liquid seal and through the exhaust orifice 33.

The pressure chamber 25 is fitted with a pipe line 34 leading to the vessel which is to be exhausted and this pipe line 34 is fitted with a valve 35 for cutting off the machine when the vacuum has been obtained in the vessel being treated.

The pipe line 34 is preferably connected by a connection with a further pipe line having a valve thereon to retain the vacuum in the vessel when once created, and a gauge may be disposed upon the pipe line between the valve and the vessel so that the vacuum obtained may be readily ascertained.

Immediately the required vacuum is obtained, the apparatus described may be removed therefrom and any further vessels treated in a similar manner, the apparatus being removed by detaching the pipe from the portion above the valve.

In operation the pressure fluid passes into the inlet pipe 22 being first split and given a rotary movement by the helix 21 such movement being maintained until it passes the by-pass 24 and the fluid is then delivered through the flared end 31 of the pipe 22 into the delivery pipe or tube 30 which is of larger diameter than the inlet pipe to allow of quick exhaust.

On passing out of the tube 30 the fluid strikes the projection 32 of the concave surface of the liquid seal chamber 29 and causes the water to swirl about the end of the tube to prevent the return of air and the air and fluid then pass through the water seal and out through the exhaust pipe.

In Fig. 4 I have shown the structure of Fig. 1 with the adjustable double conical combining tube 16, 17, discharging into the discharge chamber 29 of Fig. 2.

I claim:

1. A vacuum producing apparatus comprising an air chamber, a jet nozzle entering one end of said chamber, means in the nozzle to rotate the jet formed thereby, and a double conical combining nozzle mounted in the chamber in alinement with the jet nozzle, directly receiving the jet therefrom and ad-

justable in said chamber to and from the jet nozzle for regulating the air admission to said combining nozzle with respect to the jet.

5 2. A vacuum producing apparatus, comprising an air chamber to be exhausted, a jet nozzle entering one end of said chamber, and a double conical combining tube in the other end of said chamber alined with said nozzle, 10 and means to permit the adjustment of the tube in the end of the chamber to and from the nozzle.

3. A vacuum producing apparatus, comprising a straight double conical combining 15 tube, a closed discharge chamber into which said tube discharges, said chamber having a deflecting surface directly opposite the discharge end of said tube with a central fluid-deflecting point directed toward the tube.

4. A vacuum producing apparatus having 20 a jet device and a combining tube into which the jet device discharges, in combination with a closed discharge chamber surrounding the lower end of the tube and having a deflecting bottom provided with a point directed toward the end of said tube, said chamber having an outlet above the lower end of said tube and means to permit the longitudinal adjustment of said tube with respect to said point and jet device. 25

In testimony whereof I have signed my name to this specification in the presence of two subscribing witnesses.

JOHN WILKINSON GREIG.
